United States Patent Office.

NORMAN W. WHEELER, OF BROOKLYN, NEW YORK.

Letters Patent No. 67,471, dated August 6, 1867.

LIGHTED VENTILATOR FOR SHIPS.

The Schedule referred to in these Letters Patent and making part of the same.

TO ALL WHOM IT MAY CONCERN:

Be it known that I, NORMAN W. WHEELER, of the city of Brooklyn, county of Kings, and State of New York, have invented a new and useful "Improvement in Lighted Ventilators," applicable to the decks of ships, the roofs of houses, and to other purposes; and I do hereby declare that the following is a full and exact description of the construction and operation thereof, reference being had to the accompanying drawings, with the letters of reference marked theron, forming a part of this specification, like letters indicating the same parts in the different figures, of which—

Figure 1 is a vertical section, and
Figure 2 a plan of my "improvement in lighted ventilators," while
Figure 3 is a vertical section,
Figure 4 a plan, and
Figure 5 a sectional plan, showing one modification of my invention.

The essence of my invention consists in combining a glass top or light with any known ventilating hood, cowl, or top, in such a manner that the ventilator will also serve to transmit light to the room or space ventilated; and also in a means of closing the hood or cowl, when desired, by swinging doors, which also serve as air-deflectors, all as hereinafter described.

In figs. 1 and 2, *a* is a flanged shaft, which may be secured permanently to the deck or roof over an aperture through the same. *B*, the hood, fitted to turn around upon the shaft *a*, and guarded against leakage of falling water by the ring and cape *ll*. At the top of the hood *B* is fitted a frame, *d d*, within and to which is fitted one or more sheets or panes of glass *C*, which should be strong enough to resist any blows or shocks it will be likely to receive; and the frame should also be scuppered, as seen at *jjjj*, so that any water falling upon the glass *C* will readily run off. At the upper part of the hood *B* is fitted a visor, *h*, projecting over the opening in the hood to prevent, in a great degree, the falling of water into the opening, and so down the shaft, and to afford means of securing the deflecting doors *E E* in the proper positions. The deflecting doors *E E* are hinged to the hood at *M M* in such a way that they may be swung in to close the aperture in the hood, and prevent the entrance of water completely, and also arrest the ventilation, which it would be necessary to do in cold and rainy weather; or thrown more or less open, and held in position by pins inserted in holes, as at *i i*. At *f* is seen a cross-bar secured to the hood *B*, to which cross-bar is attached the rod *g*, by which the hood may be turned in any direction from below. At *o* is seen a section of a hollow truncated cone secured to the shaft *a*, so formed as to catch what water may have come in and trickled down the inside of the hood, and run it out through small holes at *K K*. Figs. 3, 4, and 5 represent a ventilator of ordinary construction, but fitted with a glass top, *C*, to render it a lighted ventilator, the openings *p p*, &c., being covered against rain and spray by the shields *R R*, &c., the draught in this case being always outward.

Having described my invention, I will indicate that which I consider new and useful, and for which I desire to secure Letters Patent:

1. I claim the combination of the glass top *C* with the hood *B*, or their equivalents, substantially as described.
2. I claim the hinged deflecting doors *E E*, in combination with the hood *B*, provided with a glass top, substantially as described.

NORMAN W. WHEELER.
